W. A. Brady

By

W. A. Brady, Jr.
Attorney

UNITED STATES PATENT OFFICE.

WILLIAM A. BRADY, OF OHIOPYLE, PENNSYLVANIA.

HAMMER ATTACHMENT FOR PAINTBRUSHES.

Application filed November 26, 1926. Serial No. 150,952.

This invention relates to attachments for brushes, and more particularly to an attachment for brushes of the type usually employed for the purpose of painting roofs, 5 and embodying handles arranged at an angle to the bristle mounts or heads thereof.

The invention has for one of its objects to provide a roof paint brush with an attachment which will permit it to be readily 10 used for the purpose of driving home any loose nails in the roof; and to attain this end comprehends the provision of a hammer head adapted to be secured to the upper edge of the mount or back of the brush and 15 having its face arranged in parallel relation to the handle.

With the foregoing and other objects in view, the nature of which will become apparent as the description proceeds, the invention consists of the construction, combination, and arrangement of parts herein-after fully described and claimed, and illustrated in the accompanying drawing, 20 wherein:

Fig. 1 is view in side elevation of a roof paint brush equipped with the hammer head,

Fig. 2 is a view in front elevation of the brush,

Fig. 3 is a sectional view taken on the plane indicated by the line 3—3 of Fig. 2, and

Fig. 4 is a detail perspective view of the hammer head.

Referring to the drawing by reference numerals, 1 designates the wood mount or head, 2 the bristles, and 3 the handle of a paint brush of the type usually employed for the purpose of painting roofs. The handle 3 is arranged at an angle with respect to the mount or head 1, and the latter is provided with an eye or opening 4 for the reception of the forward end of the former.

In accordance with my invention, the brush is provided with a hammer head 5 which is secured to the upper edge of the mount or head 1 thereof. The hammer head 5 comprises an elongated base 6 and a poll 7 formed integrally with and extending centrally from the base. The face of the poll 7 is inclined and arranged parallel to the handle 3 and opening 4. The base 6 is provided in its inner side with a groove 8 which extends longitudinally thereof and 55 receives the upper edge of the mount or

head 1. The sides 9 of the groove 8 are inclined so as to force the fibers of the mount or head 1 together during the application of the hammer head 5. Long screws 10 and short screws 11 secure the hammer head 5 to the mount or head 1. A pair of the screws 10 and 11 is arranged on each side of the poll 7, and the long screws 10 are arranged closer to the poll than are the short screws 11. The long screws 10 prevent the splitting of the mount or head 1. If desired white lead may be applied to the opposing surfaces of the mount or head 1 and base 6 for the purpose of preventing moisture from finding its way between these parts. 70

From the foregoing and accompanying drawing, it will be apparent that the hammer head is strong, durable, and efficient, that it may be readily applied to the brush mount or head, and that since its face is arranged in parallel relation to the handle of the brush the latter may be easily handled during the driving home of loose nails. It is recommended that the nails be painted prior to driving them home for the reason that 80 it has been found that when this is done the roof is made water-tight and the nails remain in place.

It should be understood that the drawing is merely illustrative and does not pretend to give exact proportions. Furthermore, the said drawing is illustrative of a preferred construction, it being my expectation that various changes and modifications may be made without departing from the spirit and 90 scope of my invention.

What is claimed is:—

1. A device of the character set forth, comprising a mount provided with an eye, a handle having one end positioned in the eye, a head having an elongated base and a poll projecting from the base, the head being positioned on the mount with its base in contact therewith and with the face of its poll in substantially parallel relation to the eye, 95 and attaching means engaging the base and mount.

2. A device of the character set forth, comprising a mount provided with an inclined eye, a handle having one end positioned in the eye, a head having an elongated base and a poll projecting from the base, the poll being provided with an inclined face, the head being positioned on the mount with its base in contact therewith and 110

with the face of its poll in substantially parallel relation to the eye, and attaching means engaging the base and mount.

3. A device of the character set forth, comprising a mount provided with an eye, a handle having one end positioned in the eye, a head having an elongated base and a poll projecting centrally from the base, the base being provided with a longitudinally extending groove for the reception of an edge of the mount, the head being arranged on the mount with the face of its poll in substantially parallel relation to the eye, and attaching means engaging the base and mount.

4. A device of the character set forth, comprising a wood mount, a handle secured to the mount, a metallic head having an elongated base and a poll extending from the base, the base being provided with a longitudinally extending groove for the reception of an edge of the mount, and the sides of the groove being inclined to force the fibers of the mount together during the application of the head to the mount, and attaching elements passing through the base and entering the mount. 15 20 25

In testimony whereof I affix my signature.

WILLIAM A. BRADY.
